UNITED STATES PATENT OFFICE.

MARGARET DONALDSON, OF LEXINGTON, KENTUCKY, ASSIGNOR TO SPOTSWOOD SPECIALTY COMPANY, OF LEXINGTON, KENTUCKY.

TOY.

1,122,485.

Specification of Letters Patent. Patented Dec. 29, 1914.

Application filed October 20, 1913. Serial No. 796,336.

To all whom it may concern:

Be it known that I, MARGARET DONALDSON, citizen of the United States, residing at Lexington, in the county of Fayette and State of Kentucky, have invented certain new and useful Improvements in Toys, of which the following is a specification.

This invention relates to toys and more particularly to a toy pistol which when 10 grasped in the hand and swung quickly downwardly to sighting position will produce a loud report and it is the primary aim of the invention to so construct the noise producing device that the report will 15 be much sharper and louder than if the device were constructed in the ordinary manner, the invention contemplating in this connection, the formation of the air pocket in such manner that a maximum volume of 20 air will be confined as the device is swung downwardly, which volume will be so trapped that there can be no escape of such a portion of the volume of air as would detract from the loudness of the report and 25 the sharpness thereof.

Another aim of the invention is to provide a toy of the class described which may be manufactured at little cost, will be substantial and not liable to tear or get out of 30 order, and which will possess features rendering it valuable as an advertising medium.

In the accompanying drawings: Figure 1 is a perspective view of the toy embodying 35 the present invention and illustrating the manner of using the same. Fig. 2 is a perspective view, parts being shown in section, and the side members of the toy being shown partly separated or opened. Fig. 3 is a 40 vertical longitudinal sectional view taken in a plane between the side members and illustrating the web in normal position in full lines and in unfolded or extended position in dotted lines.

In the drawings the toy is illustrated as 45 consisting essentially of two side members indicated by the numeral 1, these members being preferably formed from pasteboard blanks and being of counterpart outline and 50 the members at one end are cut so as to form a handle portion 2 preferably printed or otherwise marked to resemble the grip of a revolver and the body portions of the

members, indicated by the numeral 3, are cut so as to resemble somewhat the barrel 55 of a revolver and the said body portions are preferably printed or otherwise marked to resemble or imitate the barrel and the cartridge cylinder of a revolver. The handle portions 2 are preferably formed with 60 matching or registering openings 4 which are located so as to resemble the trigger guard, these openings being designed for the insertion therethrough of the forefinger when the handle is grasped in the hand. 65 Forwardly of the body portions 3, the side members 1 have their lower edges extending in a line with the lower edges of the said body portions but their upper edges are inclined upwardly and forwardly as indicated 70 at 5 so that the said side portions are of greater height forwardly of their body portions than at any other point and it is preferable that the extended portions thus formed and indicated by the numeral 6, 75 have printed or otherwise indicated upon them a representation of flame and also preferably a bullet.

By reference to the drawings it will be observed that the upper edges of the body 80 portions of the side members are united by a binding strip 7 which is folded over the said edges and secured thereto and which may be of cloth, paper, or any other suitable material. The edges 5 of the side members are also united by means of a binding strip indicated by the numeral 8 and it will be observed that the strips 7 and 8 are substantially continuous and, in fact, the said edges may be united by a continuous strip 85 if desired.

The web of the device is indicated by the numeral 9 and is preferably formed from a substantially triangular sheet of paper, the sheet being attached at its side edges as at 95 10, by glue or otherwise, to the forward edges of the extended portions 6 of the side members and being folded along a vertical line bisecting the base of the triangle and intersecting the apex. Normally the folded 100 web lies between the side members 1 but by reference to Fig. 1 of the drawings it will be understood that when the web is unfolded or extended so as to lie bodily beyond the forward edges of the portions 6 105 of the side members, a pocket will be formed

of which the web will constitute one wall and the side members the other walls. The web has its apex located at the upper end of the forward edges of the side members 5 so that the pocket formed is closed at its top by the binding strips 7 and 8. It will be apparent that the strips 7 and 8 serve to prevent the escape of confined air at the upper edges of the device and that 10 due to the fact that the edges 5 are inclined upwardly and forwardly the pocket is increased in depth in the direction of the forward edges of the portions 6.

It will now be apparent that when the 15 handle 2 is grasped and the arm is swung quickly downwardly with a movement imitating the act of pointing and firing a revolver, the air entering between the side members will be compressed within the 20 pocket above described and as a result the web 9 will be forced outwardly as shown in Fig. 1, producing a loud report. It will be understood that the air entering between the side members will be trapped between 25 the said members and prevented from escaping by the united upper edges of the said members and that inasmuch as the pocket is increased in height in the direction of the forward edges of the members whereby to 30 effectually trap the entering air, the report obtained will be sharp and loud and, in fact, much sharper and louder than would be the case if the side members were not provided with the portions 6 increased in height as 35 shown and described. Furthermore, a greater volume of air is compressed within the pocket than would be the case if the united edges of the side members extended throughout their entire length along the line 40 of extent of the edge 5 inasmuch as the pocket would then be decreased in depth toward its handle end whereas in the present instance it is decreased in depth only for a short distance and is rearwardly of 45 its portion 6 of a uniform depth and relatively deep.

Having thus described my invention, what I claim as new is:

1. In a toy of the class described, side members each having relatively angularly 50 extending united upper edge portions, the said edge portions matching, the side members having matching handle portions located rearwardly of their united edges, and a web attached at its side edges to the forward edges of the side members and folded to normally lie between the said side portions. 55

2. In a toy of the class described, side members of counterpart outline, the upper 60 edges of the said members throughout a portion of their length extending parallel to their lower edges and having their upper edges throughout their forward portions extending upwardly and forwardly, said edge 65 portions of the members being united, and a web having its side edges connected to the side members, the said web normally lying between the side members.

3. In a toy of the class described, a 70 pocket open at its bottom and closed at its top, the pocket for a portion of its length having a constant depth and for the other portion of its length being increased in depth toward one side thereof, and a web 75 constituting the said side of the pocket and normally lying within the pocket.

4. In a toy of the class described, side members having matching handle portions, the upper edges of the said portions being 80 united forwardly of the handle and the said side members being provided in advance of the handle with registering finger openings, and a web attached at its side edges to the side portions and normally lying between 85 the same.

In testimony whereof I affix my signature in presence of two witnesses.

MARGARET DONALDSON. [L. S.]
